UNITED STATES PATENT OFFICE.

ARCHIBALD W. PAULL AND ALONZO L. EDWARDS, OF WHEELING, WEST VIRGINIA, AS
SIGNORS TO WHEELING STAMPING COMPANY, OF WHEELING, WEST VIRGINIA, A
CORPORATION OF WEST VIRGINIA.

COLLAPSIBLE-TUBE-COATING MECHANISM FOR TUBE-PRINTING MACHINES.

Application filed August 4, 1922. Serial No. 579,633.

To all whom it may concern:

Be it known that we, ARCHIBALD W. PAULL and ALONZO L. EDWARDS, citizens of the United States of America, and residents of 5 Wheeling, county of Ohio and State of West Virginia, have invented certain new and useful Improvements in Collapsible-Tube-Coating Mechanism for Tube-Printing Machines, of which the following is a specification.

This invention relates broadly to mechanism for coating collapsible metal tubes, and it has for its primary object to provide an apparatus for applying to such tubes a protective coating of varnish immediately following the application of the ink in printing upon such tubes.

A further object is to provide mechanism of the character mentioned by which the 15 varnish is applied in a thin and evenly distributed film immediately following printing upon the tube and while said tube is borne by the carrier disk of the printing mechanism.

20 Heretofore it has been the universal practice to allow the ink applied in printing upon the tubes to dry thoroughly before the application to the tubes of the usual protective coating of varnish. This practice required that a long interval elapse between 25 the time of printing and that of coating.

The present invention aims to effect the printing and the coating of the tubes in a single operation, or in rapidly succeeding 30 operations, and with but a single handling of the tubes, employing ink and varnish compositions which allow of the application of the varnish to the wet ink without a resultant confused running, spreading or mingling of the ink with respect to the varnish; thereby not only avoiding the necessity for separate 35 handleings of the tubes, but also providing for the simultaneous drying of the ink and varnish and conserving the large factory space heretofore required in drying the varnish alone.

In describing the invention in detail, reference is herein had to the accompanying 40 drawings, in which—

Figure 1 is a top plan view of the invention;

Figures 2 and 3 are opposite side elevations of the same; and—

Figure 4 is a section taken approximately 55 on line 4—4, Fig. 1.

Referring to said drawings, 1 indicates the printing roll of an ordinary type of machine employed for printing upon collapsible metal tubes, and 2 designates the usual carrier disk by which the tubes 3 are borne into engagement with said printing roll, said disk having a plurality of tube-carrying spindles 4 disposed in spaced relation 60 on one face thereof adjacent to its peripheral edge.

Located in a position to be engaged by the spindle-carried tubes 3 immediately subsequent to engagement of the latter with the printing roll 1 is a roll 5 designed to apply 70 to said tubes a thin film-like coating of varnish. Said roll 5 is suitably journaled upon a carrier frame consisting of parallel members 6 which are superposed upon a supporting frame 7. Said members 6 have their 75 rear ends loosely mounted upon a rotating shaft 8 which is journaled in bearings 9 carried on the rear end of the frame 7 and which is driven in any appropriate manner, as by a sprocket-chain 10 connected to any suitable positively rotated shaft 11 of the printing mechanism. The front ends of said frame members 6 are seated upon the ends of upwardly directed adjusting screws 12 which are carried by said supporting frame 80 85 7 and which are adapted for adjustment for accurately positioning the roll 5 with respect to the path of travel of the spindle-carried tubes.

The coating material, or varnish, is supplied to the roll 5 from a suitably located reservoir 13 through the medium of a plurality of transfer and distributing rollers. Said reservoir comprises a box-like container of which a roller 14 constitutes a complementary portion, the inner portion of said container being shaped to conform to and being fitted closely against the convex peripheral surface of said roller, thus allowing the coating material to directly contact said roller. Disposed within said container is a downwardly and inwardly inclined flexible plate 15 having its inner edge located in seated bearing relation to said roller 14 90 95 100

below the level of the axis of the latter and designed to prevent leakage thereby of the coating material. The upper edge of said plate is attached to the outer wall of said container by means of bolts or screws 17. Adjusting screws 16 directed inward through the container have their points in pressure exerting relation to the back of said plate and are adapted for adjustment to position 10 the lower edge of the latter in proper relation to said roller.

As herein shown, the transfer and distributing rollers interposed between the reservoir 13 and the varnish-applying roll 5 consist of the roller 14, a roller 18, a roller 19 intermittently shiftable between a position in which it contacts with said roller 14 and one in which it contacts with said roller 18, and a roller 20 permanently disposed in contact both with said roller 18 and said roll 5, said rollers 14 and 18 being journaled in bearings carried by the frame members 6. As is apparent, the purpose of the various rollers interposed between the reservoir and the applying roll 5 is to provide for the distribution of the coating material in such manner that said roll will receive and effect the application to the tubes of an extremely light or thin and evenly distributed film-like coating capable of protecting the ink applied by the printing roll 1.

The roller 14 is rotated intermittently throughout a small fractional part of a revolution, a ratchet wheel 21 carried by an end or neck 21^a thereof being associated with a pivoted dog or pawl 22 carried by the upper end of a lever 23 which is pivotally mounted on said neck and which has its opposite end connected by a pitman 24 to the wrist-pin 25 of an eccentric disk 26 carried by the constantly rotating shaft 8. The shiftable roller 19 is journaled at its opposite ends in the bifurcated or forked upper ends of upwardly and rearwardly inclined arms 27 which are pivoted at their lower ends upon the opposite frame members 6. Pivoted intermediate the ends of one of said arms 27 is one end of a rod 28 which has its opposite end mounted on said shaft 8 and through which, in each revolution of said shaft, said arms are shifted to momentarily present the roller 19 in contact with said roller 14 for receiving from the latter 55 a supply of the coating material, following which said roller 19 returns by gravity into contact with the roller 18 for transferring said supply to the latter. The shaft 8 is directed through an oblong opening or slot 29 in the rod 28 and carries a cam 30 which, in each revolution thereof, engages said rod for thrusting the latter forward from its normal retracted position in engagement with the roller 18 to a position 60 in engagement with the roller 14.

The rollers 18, 20 and 5 are positively driven in any suitable manner. As herein shown, a sprocket chain 32 connects sprocket wheels 33 and 34 carried by the shaft 8 and a neck of the roller 18, respectively; and rotation is imparted to the roller 20 through interengaging gears 35 and 36 carried, respectively, by the necks of said rollers. The roll 5 carries a gear 37 in mesh with said gear 36 and through which rotation is communicated to said roll.

What is claimed is—

1. In mechanism for coating collapsible metal tubes, the combination with the printing roll and the rotating carrier-disk of a tube-printing machine, said disk having tube-carrying spindles on a face thereof, of a coating roll located adjacent to the path of travel of said spindles and adapted to be engaged by the peripheries of the tubes as the latter are advanced following contact with said printing roll, a reservoir for the coating material, and means intermediate said reservoir and said coating roll whereby material from the former is transferred to the latter.

2. In mechanism for coating collapsible metal tubes, the combination with the printing roll and the rotating carrier-disk of a tube-printing machine, said disk having tube-carrying spindles on a face thereof, of a coating roll located adjacent to the path of travel of said spindles and adapted to be engaged by the peripheries of the tubes as the latter are advanced following contact with said printing roll, a reservoir for the coating material, and means intermediate said reservoir and said coating roll for transferring an evenly distributed supply of said material from said reservoir to said coating roll.

3. In mechanism for coating collapsible metal tubes, the combination with the printing roll and the rotating carrier-disk of a tube-printing machine, said disk having tube-carrying spindles on a face thereof, of a coating roll located adjacent to the path of travel of said spindles and adapted to be engaged by the peripheries of the tubes as the latter are advanced following contact with said printing roll, a reservoir for the coating material, a roller disposed for receiving a supply of said material from said reservoir, and a plurality of transfer and distributing rollers interposed between said receiving roller and said coating roll.

4. In mechanism for coating collapsible metal tubes, the combination with the printing roll and the rotating carrier-disk of a tube-printing machine, said disk having tube-carrying spindles on a face thereof, of a coating roll located adjacent to the path of travel of said spindles and adapted to be engaged by the peripheries of the tubes as the latter are advanced following contact

- with said printing roll, a reservoir for the coating material, a roller to which material is supplied from said reservoir, means intermittently rotating said roller throughout 5 a part of a revolution, and a plurality of transfer and distributing rollers interposed between the first mentioned roller and said coating roll.
5. In mechanism for coating collapsible metal tubes, the combination with the printing roll and the rotating carrier-disk of a tube-printing machine, said disk having 10 tube-carrying spindles on a face thereof, of a coating roll located adjacent to the path 15 of travel of said spindles and adapted to be engaged by the peripheries of the tubes as the latter are advanced following contact with said printing roll, a reservoir for the coating material, a roller arranged to form 20 a complemental portion of said reservoir and to receive directly from the latter a coating of said material, means for advancing said roller intermittently, and a plurality of transfer and distributing rollers whereby 25 material is collected from the first mentioned roller and transferred to said coating roll.
6. In mechanism for coating collapsible
- metal tubes, the combination with the printing roll and the rotating carrier-disk of a tube-printing machine, said disk having 30 tube-carrying spindles on a face thereof, of a coating roll located adjacent to the path 35 of travel of said spindles and adapted to be engaged by the peripheries of the tubes as the latter are advanced following contact with said printing roll, a reservoir for the coating material, a roller arranged to form a complemental portion of said reservoir and to receive directly from the latter a coating 40 of said material, means for advancing said roller intermittently, and a plurality of transfer and distributing rollers whereby material is collected from the first mentioned 45 roller and transferred to said coating roll, one of the last mentioned rollers being intermittently shiftable into and out of contact with said first mentioned roller.

In testimony whereof we affix our signatures in presence of two witnesses.
